UNITED STATES PATENT OFFICE

154,684

DESIGN FOR A GARMENT HANGING ATTACHMENT FOR IRONING BOARDS

Al C. Hufeld, Peoria, Ill.

Application September 27, 1948, Serial No. 148,778

Term of patent 7 years

(Cl. D49—1)

To all whom it may concern:

Be it known that I, Al C. Hufeld, a citizen of the United States and a resident of Peoria, in the county of Peoria and State of Illinois, have invented a new, original, and ornamental Design for a Garment Hanging Attachment for Ironing Boards, of which the following is a specification, reference being had to the accompanying drawing, forming part thereof.

In the drawing,

Fig. 1 is a side elevational view of a garment hanging attachment for ironing boards showing my new design, the view being fragmented for convenience of illustration.

Fig. 2 is a right-hand end view of Fig. 1.

Fig. 3 is a top plan view thereof.

I claim:

The ornamental design for a garment hanging attachment for ironing boards, substantially as shown and described.

AL C. HUFELD.
